UNITED STATES PATENT OFFICE.

PERCY RUSSELL, OF SWARTHMORE, PENNSYLVANIA, ADOLPH W. SCHRAMM, OF RIVERTON, NEW JERSEY, AND ROBERT S. WOODWARD, JR., OF HAVERFORD, PENNSYLVANIA, ASSIGNEES TO ELECTRO DENTAL MANUFACTURING COMPANY, OF PHILADELPHIA, PENNSYLVANIA, A CORPORATION OF PENNSYLVANIA.

DESIGN FOR A DENTAL STAND.

59,933.

Specification for Design.

Patented Dec. 6, 1921.

Application filed October 29, 1920. Serial No. 420,558. Term of patent 7 years.

To all whom it may concern:

Be it known that we, PERCY RUSSELL, ADOLPH W. SCHRAMM, and ROBERT S. Woodward, Jr., citizens of the United States, residing in Swarthmore, Delaware county, Pennsylvania, Riverton, Burlington county, New Jersey, and Haverford, Montgomery county, Pennsylvania, respectively, have invented a certain new, original, and ornamental Design for a Dental Stand, of which the following is a specification, reference

being had to the accompanying drawings, forming part thereof, in which the figure is a perspective view of the dental stand forming the subject of our new, original, and ornamental design.

We claim:

The ornamental design for a dental stand, substantially as shown.

PERCY RUSSELL.

ADOLPH W. SCHRAMM.

ROBERT S. WOODWARD, JR.
